Primary Examiner — Jennifer L Watkins*Assistant Examiner* — Christine Tucci(74) *Attorney, Agent, or Firm* — Banner & Witcoff, Ltd.(57) **CLAIM**

The ornamental design for a shoe, as shown and described.

DESCRIPTION

FIG. 1 is a front bottom perspective view of a shoe showing my new design;

FIG. 2 is a bottom view thereof; and,

FIG. 3 is a rear bottom perspective view thereof.

The even-length broken lines immediately adjacent to the photographic area define the bounds of the claimed design and form no part thereof. The unshaded areas between the even-length broken lines represent grooves which form no part of the claimed design. The uneven-length broken lines depicting the remainder of the shoe form no part of the claimed design.
